UNITED STATES PATENT OFFICE.

THOMAS A. GOODE, OF KANSAS CITY, KANSAS, ASSIGNOR OF ONE-THIRD TO CALVIN M. HINDS, OF KANSAS CITY, MISSOURI, AND ONE-THIRD TO JULIUS BRAGG, OF HUNTINGTON, OREGON.

COMBINATION-PADLOCK.

1,307,442.

Specification of Letters Patent. Patented June 24, 1919.

Application filed March 18, 1919. Serial No. 283,332.

To all whom it may concern:

Be it known that I, THOMAS A. Goode, a citizen of the United States, residing at Kansas City, in the county of Wyandotte 5 and State of Kansas, have invented a certain new and useful Improvement in Combination-Padlocks, of which the following is a specification.

My invention relates to improvements in 10 combination padlocks.

The object of my invention is to provide a combination padlock which is simple in construction, which is cheap to manufacture, which is strong and durable and not liable 15 to get out of order, which permits of a quick and easy change in the combination, which affords a maximum of efficiency and secures it from unauthorized tampering, and which may be quickly unlocked by a person 20 acquainted with the combination.

A further object of my invention is the provision of novel means for holding the tumblers in the proper position when the hasp is withdrawn.

25 The novel features of my invention are hereinafter fully described and claimed.

In the accompanying drawings which illustrate the preferred embodiment of my invention,

30 Figure 1 is a side elevation of my improved padlock, shown in the locked position.

Fig. 2 is a horizontal sectional view on the line 2—2 of Fig. 8.

35 Fig. 3 is a perspective view of the tumbler locking lever.

Fig. 4 is a cross section on the line 4—4 of Fig. 5.

40 Fig. 5 is a central view shown partly in vertical section and partly in side elevation of the padlock in the locked position.

Fig. 6 is a bottom view of the padlock.

Fig. 7 is a side elevation, partly broken away, of the hasp.

45 Fig. 8 is a side elevation of the casing, the two members of which are shown in the open position.

Fig. 9 is a horizontal sectional view on the line 9—9 of Fig. 5.

50 Similar reference characters designate similar parts in the different views.

1 designates a hasp which is of inverted U-shape of the ordinary type and which is

provided on the inner side of each of its arms with notches 2 respectively adapted to 55 receive horizontally disposed tumblers 3 which are mounted one above the other on a vertical support comprising a vertical pin 4 and a vertical stem 5 disposed in alignment one above the other, the pin 4 being 60 rigidly secured at its upper end in a horizontal top member 6 of one of the members 7 of the casing which is hinged by a vertical pintle 8 to the other casing member 9, as is best shown in Figs. 2 and 8. 65

The stem 5 is rotatably mounted in the bottom member 10 of the casing member 7.

The stem 5 extends upwardly from a horizontal disk 11 which is provided with a circular row of graduations 12 which are 70 adapted to register with an indicating mark 13 on the under side of the bottom member 10, as is shown in Fig. 6. The disk 11 is turned by means of a central downwardly extending thumb piece 14. 75

Referring particularly to Fig. 5, it will be noted that the three uppermost tumblers 3 are rotatably mounted on the pin 4, and the lowermost tumbler 3 is rigidly secured 80 to the stem 5.

The tumblers 3 are spaced apart from each other by collars 15 rigidly attached to the pin 4. The lowermost tumbler 3 has mounted in it an upwardly extending pin 16, which is adapted to be removably mounted in any one of an annular row of vertical holes 17 arranged concentrically around the stem 5, each of the other tumblers 3 is provided with a similar circular row of holes 17 in the manner illustrated in Fig. 4. 90

A vertical pin 18 is mounted in one of the holes 17 of the tumbler 3 next above the lowermost tumbler, as shown in Fig. 8. The pin 18 extends downwardly in the path of the pin 16 and upwardly in the path of a pin 19, which is mounted in one of the holes 17 of the tumbler next above. The pin 19 extends upwardly into the path of a pin 20, which is mounted in one of the holes 17 in the uppermost tumbler 3 and which projects downwardly therefrom, as shown in Figs. 5 and 8. 100

By adjusting the pins 16, 18, 19 and 20 in different positions in holes 17, the combination may be changed at will. Each tumbler 105 3 is provided on its periphery with two

diametrically opposite notches 21 adapted to respectively receive the arms of the hasp 1, in the manner shown in Fig. 4.

The casing member 9 is provided with 5 two vertical holes 22 adapted to have inserted therein the two arms of the hasp 1. The top member 6 is provided with two vertical holes 23 adapted to respectively receive the arms of the hasp 1.

10 The bottom member 10 is provided with two recesses 24 on its upper side adapted respectively to receive the lower ends of the arms of the hasp 1. As the arms of the hasp 1, when in operative position, extend 15 through the holes 22 in one member 9 of the casing, and through the holes 23 in the top member 6 of the other casing member 7, the two hinged members 7 and 9 will be held by the hasp in the lowest position.

20 When the casing member 9 is swung to the closed position shown in Figs. 1, 4, 5 and 9, the holes 22 and 23 and recesses 24 will be in vertical alinement, so as to admit the arms of the hasp 1; when the tumblers 3 25 are all turned to a position in which the notches 21 will be disposed in two vertical rows. At such time, the hasp 1 may be inserted into or removed from the casing. To hold the tumblers 3 in this position, and to 30 prevent their accidental displacement therefrom, while the hasp is out of the casing, I provide the following described releasable locking mechanism:

A U-shaped lever 25, Fig. 3, has its horizontal arms respectively provided with holes 26 and 27, through which respectively extend two vertical pins 28 and 29, Fig. 8, mounted respectively in the top member 6 and the bottom member 10 of the casing 35 member 7. The vertical portion which connects the arms of the lever 25 is normally forced inwardly by a suitable spring 30, Fig. 9, and Fig. 2, so as to enter notches 31, two of which are provided in the periphery of each tumbler 3 in diametrically opposite positions, as shown in Fig. 4. When one set of notches 31 is in alinement with and adapted to receive the vertical part of the lever 25, the notches 21 will be disposed 45 so as to receive the arms of the hasp 1.

In order that the lever 25 may be disengaged from the tumblers 3, when the hasp 1 is inserted in the locked position shown in Fig. 5, the lower arm of the lever 25 is provided with a lateral extension 32, which is beveled on its upper side and which is adapted to be struck by the lower end of one of the arms of the hasp 1 and moved laterally thereby a distance sufficient to swing 55 the lever 25 out of the adjacent notches 31, as shown in Figs. 4 and 9. The member 9 is held releasably in the closed position shown in Figs. 1, 4, 5 and 9, when the hasp 1 is removed from the casing, by means of 60 two horizontal screws 33 shown in Figs. 1

and 9. By removing the screws 33 and the hasp 1, the casing member 9 may be swung to the open position. By then removing a pin 34 which attaches the lowermost tumbler 3 to the stem 5, and by removing pins 35 70 which attach the three lowermost collars 15 to the pin 4, the tumblers 3 may be removed and the pins 16, 18, 19 and 20 may then be mounted in the holes 17 such as will effect the required new combination. The 75 removed parts may then be replaced in operative position, with the notches 21 in alinement with the holes 23, after which the casing member 9 is swung to the closed position and reattached by the screws 33 to the 80 casing member 7. At this time, the lever 25 will enter the adjacent notches 31 of the tumblers 3, thereby holding the tumblers from movement until the hasp 1 is inserted in the closed position shown in Fig. 5. 85

To lock the hasp in the closed position, the disk 11 is turned by means of the thumb piece 14, thereby turning the lowermost tumbler 3 through the intermediacy of the stem 5. By continued turning of the thumb piece 90 14, the pin 16 will engage and carry with it the pin 18 and the tumbler attached thereto. The pin 18, upon continued turning of the finger piece 14 will engage and carry with it the pin 19, which in turn will engage and carry with it the pin 20. By means of such turning of the thumb piece 14, the tumblers 3 may be brought to positions in which at least some of them will enter the notches 2 of the hasp 1, thus locking the 100 hasp in the casing members 9 and 7.

To unlock the padlock, the thumb piece 14 is turned continuously in one direction, for three or more turns and to a position in which the indicating mark 13 will register 105 with the first graduation of the combination, at which time the uppermost tumbler 3 will be in the unlocking position, that is with its notches 21 in register with the holes 23. The thumb piece 14 is then turned in the 110 reverse direction two revolutions and to the second number of the combination. This sets the second tumbler from the top in the unlocking position. The thumb piece 14 is then turned in the opposite direction 115 one turn and to the next number of the combination. This will set the third tumbler from the top in the unlocking position. The thumb piece 14 is reversed in rotation to the fourth number of the combination. All 120 the tumblers will now be in the unlocking position with their notches 21 in alinement with the holes 23, and the hasp can be removed from the casing. When this has been done, the spring 30 will force the lever 25 125 into the adjacent notches 31 of the tumblers, thus locking the latter from accidental displacement from the unlocking position.

Each of the tumblers 3 is provided with two oppositely disposed peripheral notches 130

31 in order that the locking lever 25 may enter one of the notches irrespective of the relative arrangement of the pins 16, 18, 19 and 20 in the holes 17.

5 I do not limit my invention to the structure shown and described, as modifications, within the scope of the appended claims, may be made without departing from the spirit of my invention.

10 What I claim is:—

1. In a combination padlock, a casing comprising two members hinged together, provided each with a hole, said holes registering with each other when the members are in the closed position, and a hasp adapted to be removably inserted in said holes for holding the members in the closed position.

2. In a combination padlock, a casing comprising two members hinged together provided each with a hole, said holes registering with each other when the members are in the closed position, manually operated tumblers in said casing movable to and from the unlocked position, and a hasp removably insertible through said holes when the tumblers are in the unlocked position for holding said members in the closed position, the tumblers in the locked position holding the hasp from withdrawal from said holes.

3. In a combination padlock, a casing comprising two members hinged together and movable to and from a closed position and provided each with a hole, said holes registering with each other when the members are in the closed position, manually movable tumblers in said casing, each having a peripheral notch, said notches registering with said holes when the tumblers are in the unlocked position, and a hasp removably insertible to and from the locked position through said holes and said notches for holding said members in the closed position, the hasp having notches adapted to respectively receive said tumblers when the latter are moved from the unlocked position.

4. In a combination padlock, a casing, a hasp removably insertible therein, tumblers rotatably mounted on the same axis in said casing, each tumbler having means for transmitting rotation to the tumbler next adjacent, manually operated means for rotating one of the tumblers, the tumblers in the unlocked position permitting the insertion and removal of the hasp, and in the locked position holding the hasp from removal from

the locking position, a locking member adapted to releasably engage all of said tumblers for holding them in the unlocked position, when the hasp is withdrawn, the hasp when inserted to the locking position moving said locking member out of engagement with said tumblers, and means for moving the locking member into engagement with said tumblers when the hasp is withdrawn from the casing.

5. In a combination padlock, a casing, a hasp removably insertible therein, tumblers rotatable in said casing on the same axis, a locking lever pivoted to the casing and adapted to engage and hold said tumblers from turning when the latter are in the unlocked position, and a spring for forcing the lever to the locking position, the hasp when moved to the locking position engaging and swinging said locking lever to the unlocked position.

6. In a combination padlock, a casing, tumblers rotatable therein, each having a peripheral notch, the notches being in alinement when the tumblers are in the unlocked position, a locking member in said casing and movable into said notches when the latter are in alinement for holding the tumblers from turning, means for normally forcing the locking member into said notches, and a hasp removably insertible into said casing when the tumblers are in the unlocked position, the hasp engaging and moving the locking member to the unlocked position when the hasp is moved to the locking position.

7. In a combination padlock, a casing, tumblers rotatable therein, each having a peripheral notch, the notches being in alinement when the tumblers are in the unlocked position, a locking lever pivoted in said casing, a spring for swinging the lever into said notches when the latter are in alinement, and a hasp removably insertible in said casing when the tumblers are in the unlocked position, the hasp engaging and swinging the locking lever to the unlocked position out of said notches when the hasp is moved to the locking position in said casing, the tumblers when turned from the unlocked position engaging and holding the hasp in its locked position.

In testimony whereof I have signed my name to this specification.

THOMAS A. GOODE.
